UNITED STATES PATENT OFFICE.

LEWIS H. LAMONT, OF CHICAGO, ILLINOIS.

THERMOSTATICALLY-CONTROLLED HEATING ELEMENT.

Application filed September 18, 1922. Serial No. 588,759.

To all whom it may concern:

Be it known that I, LEWIS H. LAMONT, a citizen of the United States, and a resident of the city of Chicago, in the county of Cook and State of Illinois, have invented 5 certain new and useful Improvements in a Thermostatically-Controlled Heating Element; and I do hereby declare that the following is a full, clear, and exact description 10 of the same, reference being had to the accompanying drawings, and to the numerals of reference marked thereon, which form a part of this specification.

This invention relates to thermostatically 15 controlled heating elements for heating the fuel supplied to hydrocarbon motors with particular reference to automotive vehicle power plants wherein an aid to easy starting of a cold motor is a desirable characteristic. 20 It is an important object of this invention to provide improved means for heating the hydrocarbon fuel supplied to an engine to assist vaporization of at least the lighter elements thereof to render starting of an 25 otherwise cold engine comparable in ease with starting a warm engine.

It is a further important object of this invention to provide improved thermostatic means for controlling the heating effect of 30 such a heating element.

It is still another important object of this invention to provide improved thermostatic means for opening the circuit of an electrical heating element when it reaches a 35 predetermined temperature and thus to release a solenoid operated switch to render the entire device inoperative.

It is another object of this invention to provide means for breaking the circuit 40 through the heating element at a definite temperature if the solenoid switch should fail to function properly at a somewhat lower temperature, in order to guard against the danger of fires or explosions due to a 45 neglected and overheated element.

It is a further object of this invention to provide a device to assist in starting internal combustion engines that can be switched on and which will automatically cut off the 50 supply of current as soon as its work has been done, as evidenced by the heating element reaching a certain temperature.

Other and further important objects of 55 this invention will be apparent from the disclosures in the drawings and specifications.

The invention (in a preferred form) is

illustrated in the drawings and hereinafter more fully described.

On the drawings:

Figure 1 is an elevation of an automobile 60 engine with one form of the device of this invention attached thereto.

Figure 2 is a sectional view of one form of this device.

Figure 3 is a sectional view 65 of one form of this device, at right angles to that view shown in Figure 2.

Figure 4 is a sectional view of the solenoid switch used with the heating element of this 70 invention.

Figure 5 is an end view of the switch of 75 Figure 4.

Figure 6 is an end view of the heating element of Figures 2 and 3.

Figure 7 is a section on the line 7—7 of 80 Figure 2.

Figure 8 is an electrical wiring diagram of the device of this invention as shown in the preceding figures.

Figure 9 is an elevation of a modified 85 heating element.

Figure 10 is a section on the line 10—10 of Figure 9.

Figure 11 is an electrical wiring diagram 85 of the modification disclosed in Figures 9 and 10.

As shown on the drawings:

A typical automotive power plant is shown in Figure 1 wherein the numeral 1 designates an engine provided with the 90 usual appurtenances including an intake manifold 2, a carburetor 3, and a fuel supply pipe 4 leading thereto. A device 5 embodying the features of this invention is inserted between the carburetor and fuel supply pipe. An instrument board or dash 6^a carries a switch mechanism 6 controlling the 95 operation of the device 5.

The heating device comprises a tubular body portion 5 having a hollow offset boss 7 tapped for an outlet piping connection 8 intended to attach to the usual carburetor fuel supply connection. The fuel supply pipe 4 is connected at a tapped inlet 9 in the other end of the body portion. Inserted 105 in the tubular body portion 5 is an electrical heating element 10 of any well known construction, with an insulated terminal 11.

A separate compartment 12 is formed on one side of the body portion 5 to house a 110 thermostatic circuit breaker embracing a stationary insulated post 13 having a terminal

14 outside the compartment and having a screw 15 inserted therein to form an adjustable contact point normally engaging with a strip of thermostatic metal 16 secured to the body portion and hence grounded thereto.

10 The switch mechanism comprises a pull switch 17 normally held open by a spring 18 on the stem 19. A solenoid 20 acts to hold the switch closed when once pulled out. Terminals 21, 22, 23 are provided on the case for wiring as hereinafter described in connection with the wiring diagram.

15 The wiring diagram shown in Figure 8 embraces a single wire battery system although it is to be understood that this invention is adapted to be connected into any type of ignition and lighting electrical system in common use today. As shown one terminal 20 of a battery 24 is grounded as at 25 and a lead 26 from the other terminal goes to terminal 21 on the switch 6 and thence to the pull out switch 17. From the switch 17 one lead 27 goes from the terminal 22 to the heating element terminal 11, the other end of the heating element being grounded to the body portion 5. Another lead 28 from the switch 17 connects with the solenoid coil 20 and thence through the terminal 23 to the thermostat terminal 14 where it is normally grounded through the thermostatic strip 16 to the body portion.

30 The operation of the above described embodiment of this invention is comparatively simple. Pulling out the handle of the switch mechanism closes the switch 17, energizing both the heater coil 10 and the solenoid 20. The latter holds the switch stem outwardly as long as this circuit is maintained through the thermostatic strip. The solenoid resistance is of course sufficient to reduce the flow of current therethrough to an amount not great enough to cause a serious drain on the source of electrical energy. 45 As the heating element warms up it approaches a temperature sufficient to cause the thermostatic metal strip to break the circuit through the solenoid which then releases the switch stem allowing the spring thereon to open the heating element circuit permanently, so that this device can be brought into service with the knowledge that after a short lapse of time the device will automatically cut itself off the line without further attention.

50 A slightly modified form of this device is shown in Figures 9 to 11 wherein a second thermostat terminal 29 on a separate insulated post 30 having a terminal 31 engages with an insulated contact 32 on the thermostatic metal strip, which contact is connected to the heating element terminal 11 by a connector 33.

55 The wiring diagram for this modification is similar in principle to that described here-

inbefore, but for the sake of clearness will be briefly considered herein.

60 The wiring up to the switch mechanism 17 and from there through the thermostatic terminal 14 and contact 15 to ground is exactly the same as in the previously described form. The other lead 27^a for the heating element in this modification leads to the terminal 31 and thence through the contact 29 to the insulated contact 32 on the thermostatic strip 16. The insulated contact 32 is permanently wired to one terminal of the heating element 10, the other terminal of this element being grounded as before.

65 The operation of this modification is similar to that previously described except that if the switch mechanism fails to release for any reason when the thermostatic contact 15 opens, a further rise in the temperature of the heating element causes the additional insulated contact 32 to open, thus cutting off the heating element until it has cooled sufficiently to allow the contact to close again. This arrangement is of course provided simply for safety if the regular mechanism fails to function for any reason.

70 I am aware that numerous details of construction of my invention may be varied through a wide range without departing from the principles of my invention, and I therefore do not purpose limiting the patent granted otherwise than necessitated by the prior art.

75 I claim as my invention:

80 1. A heating device for fuel supply lines comprising an electrical heating element, a switch adapted to automatically maintain a closed electrical system until the heater element reaches a definite temperature and a thermostat adapted to permanently release 85 said switch upon attaining said definite temperature.

85 2. A device of the class described comprising an immersion electric heating element, a casing therefor having inlet and outlet connections for fuel supply pipes, a thermostatic control regulator therefor, and a solenoid switch mechanism permanently released by breaking the circuit through said thermostatic control.

90 3. A device of the class described comprising an immersion electric heating element, a casing therefor having inlet and outlet connections for fuel supply pipes, a thermostat attached to said casing adapted to open an electrical circuit at a predetermined temperature, and a spring-impelled switch mechanism released by said thermostat.

95 4. A device of the class described comprising an immersion electric heating element, a casing therefor having inlet and outlet connections for fuel supply pipes, a thermostat attached to said casing adapted to open an electric circuit at a predetermined 100

temperature, a pull switch in said electrical circuit, and a solenoid in said circuit adapted to hold said switch closed until said thermostat operates.

5 5. In a fuel preheating device, an electric heating element, a solenoid switch in the circuit adapted to be held in contact by the current energizing the heating element, and a thermostat adapted to break the circuit 10 and thereby release the solenoid switch upon reaching a desired temperature.

6. In a fuel preheating device, an electric heating element, a solenoid in circuit therewith, a normally open switch operatively 15 connected to said solenoid and adapted to be held closed thereby, and a thermostat in the circuit adapted to open the circuit at a pre-determined temperature to cause said solenoid to release said switch.

20 7. A heating device comprising an electric heating element, a switch controlling the circuit, a solenoid in the circuit adapted to hold

the switch closed against spring pressure, a thermostat in the circuit adapted to open at a definite temperature to cause the solenoid 25 to release the switch, and means for breaking the circuit at a higher temperature in case the switch fails to open when released by the solenoid.

8. A heating device of the class described 30 comprising an electric heating element, a solenoid switch in circuit therewith, a thermostat controlling the operation of the solenoid switch, and a secondary terminal on the thermostat adapted to open the circuit 35 upon failure of the solenoid switch.

In testimony whereof I have hereunto subscribed my name in the presence of two subscribing witnesses.

LEWIS H. LAMONT.
